UNITED STATES PATENT OFFICE

92,124

DESIGN FOR A HEATER

Stanley F. Zuck, Ann Arbor, Mich., assignor to
The Independent Stove Company, Owosso,
Mich., a corporation of Michigan

Application December 30, 1933, Serial No. 50,263

Term of patent 14 years

To all whom it may concern:

Be it known that I, STANLEY F. ZUCK, a citizen of the United States of America, residing in the city of Ann Arbor, in the county of Washtenaw, in the State of Michigan, have invented a new, original, and ornamental Design for a Heater, of which the following is a specification, reference being had therein to the accompanying drawing forming a part thereof, wherein:

The figure is a front perspective view of the heater showing my new design.

I claim:

The ornamental design for a heater substantially as shown.

STANLEY F. ZUCK.
